NONGURGLING DEMIJOHN

Carlos Ernesto de Sá Cardoso, Lisbon, Portugal

Application September 7, 1950, Serial No. 12,092
In Portugal March 11, 1950

Term of patent 14 years

(Cl. D58—25)

To all whom it may concern:

Be it known that I, Carlos Ernesto de Sá Cardoso, a citizen of Portugal, residing at 13 Rua das Janelas Verdes, Lisbon, Portugal, have invented a new, original, and ornamental Design for Non-Gurgling Demijohn, of which the following is a specification, reference being had to the accompanying drawings, forming a part hereof, and wherein:

Figs. 1 and 2 are perspective views of a non-gurgling demijohn, showing my new design, Fig. 2 being a view from the left side of Fig. 1; and Fig. 3 is a top plan view of the same.

I claim:

The ornamental design for a non-gurgling demijohn, substantially as shown.

CARLOS ERNESTO DE SÁ CARDOSO.
